SHEET METAL CLAMP

Frank C. Wallace, North Hollywood, Calif., assignor to Herman H. Helbush, Los Angeles, Calif.

Application November 27, 1944, Serial No. 565,316

5 Claims. (Cl. 85—5)

1

My present invention relates to sheet metal clamps of the type adapted to be inserted in registering perforations in superimposed sheets to temporarily clamp the sheets together with the holes in alignment.

In general, such clamps utilize a tubular body having an end wall presenting a sheet-engaging surface and through an axial opening in which wall a retaining pin reciprocates, the pin being urged retracted by means of a compression spring in the body. The outer end of the retaining pin is enlarged to provide a shoulder which serves as the other sheet-engaging member. In use a retaining pin is inserted through registering holes in two or more superimposed work sheets and the sheets are resiliently clamped between the body end wall and the enlarged outer end of the retaining pin.

A novel characteristic of my present clamp resides in its feature of adjustability to suit work sheets of different thicknesses; that is, in my improved clamp the end wall of the clamp body is carried by a threaded sleeve so that the work-engaging surface of the end wall may be adjustable towards and away from the work-engaging shoulder provided by the outer end portion of the retaining pin.

Another novel characteristic of my invention resides in the construction which renders it suitable for exerting unusually high clamping pressures without injuring the work sheets.

Another object of the invention resides in the novel and efficient means by which I mount the retaining pins in the plunger element.

An additional object is the provision in such a clamp of improved means for retaining the spreader bar in the body.

Another object of the invention is the provision in such a clamp of means of protracting the retaining pins against the pressure of the retracting spring without use of a separate tool.

Those familiar with the art will observe still further features of novelty and advantage by reading the following detailed description of a presently preferred embodiment of the invention which I illustrate in the accompanying drawings, it being understood, of course, that within its broader scope as defined by the annexed claims, my invention is capable of being embodied in other physical forms differing specifically from the adaptation now to be described.

In the accompanying drawings

Fig. 1 is a longitudinal section;

Figs. 2, 3, 4 and 5 are sectional views taken on lines 2—2, 3—3, 4—4, 5—5, respectively, of Fig. 1;

2

Fig. 6 is a perspective of an end portion of the clamp with the adjusting sleeve, lock nut and the retaining member removed;

Fig. 7 is a longitudinal section showing the retaining member protracted; and

Fig. 8 is a side elevation showing the device in clamping position.

The numeral 5 denotes a body having a longitudinal bore 6 presenting an enlarged diameter 10 inner or right-hand end portion 6a providing a shoulder 7.

Each end of the body is externally threaded and on its inner end I thread a cap 9 having an axial opening 10 of smaller diameter than the bore 6a.

15 On the outer end of the body I threadedly mount a sleeve 15 having an end wall 16 presenting an axial opening 17. A lock nut 18 is also threadedly mounted on the body for locking engagement with the inner end of the sleeve 15.

Reciprocally mounted in the bore 6 there is a retaining member comprising a plunger 20 whose inner end has sliding fit in the bore 6 and whose reduced externally threaded shank portion 21 is threaded into a socket 22 in the stem portion 23.

25 The latter portion has a headed outer end 24 which is engaged by one end of a compression spring 25. The opposite end of the spring bears against the shoulder 7.

Also forming a part of the retaining member

30 I provide a pair of oppositely disposed retaining pins 30 having their respective inner ends fitting in a socket in the inner end of plunger 20, the pins having laterally inwardly projecting inner end portions 32 which engage behind a cross pin

35 33 extending through the sides of the plunger to hold the retaining pins in the socket. The retaining pins project outwardly through the open left-hand end of the body and through the opening 17 in the sleeve and wall 16, having enlargements 35 at their outer ends to provide shoulders 36 facing the end wall 16. The pins 30 are protractable and retractable through the end wall 16 upon movement of the plunger and are adapted to be inserted through registering perforations

40 45 in work sheets 8 (see Figs. 7 and 8), the outer surface of the end wall 16 bearing against the adjacent surface of one of the work sheets and the shoulders 36 engaging the adjacent surface of the other sheet (see Fig. 8), so that the sheets

50 are clamped between the shoulders 36 and the end wall 16.

Each of the retaining pins has a beveled inner surface 40 and to spread the pins apart I provide a T-shaped spreader bar 45 having a central leg 45a and a cross arm 45b. The spreader bar

is secured in the body between the retaining pins by means of a snap ring 48 which fits in a complementary groove in the bore 6. The outer or left-hand end of the body 5 is provided with diametrically opposite longitudinal slots 50 into which the cross arm of the spreader fits, the inner ends of the slots providing a stop to prevent inward longitudinal movement of the spreader bar relative to the body and the snap ring serving as a stop to prevent outward longitudinal movement of the spreader bar.

In Fig. 1 the headed right-hand end 24 of the plunger is shown as abutting the inner surface of the cap 9, thus preventing any further retractive movement of the retaining pins. If the work sheets S to be clamped together have a combined thickness of, say, one-half inch, the sleeve 15 is rotated until it occupies the desired position of adjustment for such thickness, which position will be indicated by registration of the appropriate indicia of the scale 55, provided on at least one of the retaining pins, with the outer surface of the end wall. The plunger is then moved inwardly of the body by a conventional clamp-operating tool, not shown, which tool has a portion entering the opening 18 to engage and push inwardly on the head 24 while the clamp body is held against longitudinal movement by a portion of the clamp-operating tool engaging in the annular recess 57 provided between the ends of the clamp body. This inward movement of the plunger will protract the retaining pins 30 until the beveled surfaces 40 of the pins pass over the outer end of the leg 45a of the spreader bar (Fig. 7). The retaining pins will spring together so that their enlarged outer ends may be inserted through the registering perforations P in the work sheets. By then releasing the inward pressure on the plunger, the spring 25 will retract the retaining pins until the shoulders 36 engage the outermost work sheet around the perforation, the retaining pins then having been again spread apart by riding back over the outer end of the stationary spreader bar (Fig. 8).

By virtue of the adjustable sleeve 15 it is possible to prevent any injury to the work sheets S in case the spring 25 is strong enough to exert enough clamping force to tend to imbed the shoulders 36 or the end wall 16 in the surface at the work sheets, because by adjusting the sleeve 15 the clamp will securely hold the sheets together but will not tend to draw the enlarged ends 35 of the pins through the perforations.

I claim:

1. A sheet metal clamp comprising a body having a longitudinal bore, a sleeve threaded on the outer end of the body for axial adjustment relative thereto, said sleeve having an end wall providing a sheet-engaging surface and presenting an axial opening, a retaining member reciprocally mounted in the bore for protraction and retraction through said opening, said retaining member having a pair of laterally expandable pins each presenting a lateral projection at its outer end providing a sheet-engaging shoulder facing said end wall, a spreader member stationarily carried by the body and disposed between said pins for laterally spreading said pins apart upon retractive movement of the retaining member, and spring means for acting between the

body and retaining member to exert retractive pressure on the latter.

5 2. The clamp of claim 1 wherein the body presents a pair of diametrically opposite longitudinal slots in its outer end portion and wherein said spreader member is mounted in said slots and disposed between the pins.

10 3. The clamp of claim 1 wherein the body presents a pair of diametrically opposite longitudinal slots in its outer end portion and wherein said spreader member is disposed between the pins and having a cross arm portion mounted in said slots and a central elongated portion projecting outwardly through said opening, and a snap ring carried by the body in position to prevent outward escape of the cross arm portion of the spreader bar from the slots.

15 4. A sheet metal clamp comprising a body having a longitudinal bore, a sleeve threaded on the outer end of the body for axial adjustment relative thereto, said sleeve having an end wall providing a sheet engaging surface and presenting an axial opening, a retaining member reciprocably mounted in the bore for protraction and retraction through said opening, said retaining member comprising a plunger slidably mounted in the bore, a spring urging the plunger into retracted position, said plunger presenting a socket in its inner end, a pair of oppositely disposed pins having laterally disposed inner ends mounted in said socket and a cross pin mounted in the plunger and extending across said socket between the inner end portions of the pins, and a spreader member stationarily carried by the body for spreading engagement with the oppositely disposed pins.

20 5. A sheet metal clamp comprising a body having a longitudinal bore, a sleeve threaded on the outer end of the body, said sleeve having an outer end wall providing a sheet engaging surface and presenting an axial opening, a plunger mounted to reciprocate in the bore of the body, said plunger carrying a retaining member projecting outwardly through said opening and having a lateral portion disposed in opposed relation to the work-engaging surface of the sleeve whereby to engage work therebetween, spreader means fixed to the body and disposed to engage and laterally move the retaining member upon movement of the plunger inwardly of the body, and spring means carried by the body and cooperating with the plunger to urge the latter inwardly of the body, said sleeve being axially adjustable relative to the body.

25 6. A sheet metal clamp comprising a body having a longitudinal bore, a sleeve threaded on the outer end of the body, said sleeve having an outer end wall providing a sheet engaging surface and presenting an axial opening, a plunger mounted to reciprocate in the bore of the body, said plunger carrying a retaining member projecting outwardly through said opening and having a lateral portion disposed in opposed relation to the work-engaging surface of the sleeve whereby to engage work therebetween, spreader means fixed to the body and disposed to engage and laterally move the retaining member upon movement of the plunger inwardly of the body, and spring means carried by the body and cooperating with the plunger to urge the latter inwardly of the body, said sleeve being axially adjustable relative to the body.

30 7. A sheet metal clamp comprising a body having a longitudinal bore, a sleeve threaded on the outer end of the body, said sleeve having an outer end wall providing a sheet engaging surface and presenting an axial opening, a plunger mounted to reciprocate in the bore of the body, said plunger carrying a retaining member projecting outwardly through said opening and having a lateral portion disposed in opposed relation to the work-engaging surface of the sleeve whereby to engage work therebetween, spreader means fixed to the body and disposed to engage and laterally move the retaining member upon movement of the plunger inwardly of the body, and spring means carried by the body and cooperating with the plunger to urge the latter inwardly of the body, said sleeve being axially adjustable relative to the body.

35 FRANK C. WALLACE.
